Filed Dec. 21, 1964, Ser. No. 83,105

Term of patent 14 years

(Cl. D57—1)

FIG. 4

FIG. 5

FIG. 6

FIG. 1 is a top plan view of a pair of eyeglasses showing my new design;

FIG. 2 is a front view thereof;

FIG. 3 is a side view thereof taken from the left side of the eyeglasses shown in FIG. 2, the side not shown being substantially of the same appearance as the side shown;

FIG. 4 is a top plan view of a modified form of the pair of eyeglasses shown in FIG. 1;

FIG. 5 is a front view of the modified form; and

FIG. 6 is a side view of the modified form taken from the left side of the eyeglasses shown in FIG. 5, the side not shown being substantially of the same appearance as the side shown.

The drawing is stippled in FIG. 5 to show contrast.

My design for the eyeglasses disclosed is characterized by the chamfered end portions of the frame at the front thereof as shown.

I claim:

The ornamental design for a pair of eyeglasses, substantially as shown and described.
